UNITED STATES PATENT OFFICE.

ARTHUR PATTERSON, OF COVINGTON, KENTUCKY.

CLOSET.

Application filed June 7, 1926. Serial No. 114,074.

My invention relates more particularly to water closets or toilets.

One of the salient features of my invention consists in dispensing with the usual flushing tank, and directing a flow of water directly into the closet bowl from a water supply pipe and in providing a small tank to provide a limited amount of water to form a seal in the closet bowl against escape of gases.

In this way I save considerable water thus cutting down the operating expenses and providing more direct and dependable operation of such devices.

The direct water flushing stream and the filling of the small tank for water sealing purposes for the closet are operated simultaneously and the flushing stream operates just long enough to allow the small tank to fill; when the water is cut off the water in the small tank drains down into the auxiliary bowl or receptacle which holds the water seal.

The advantages and features of my invention will readily become apparent from the following specification.

In the accompanying drawings, forming a part of this specification:

Fig. 1, is a side elevation, the water holding tank, which acts as a flush tank, being partly broken away, to show construction,

Fig. 2, is a plan section, taken on line 2—2 of Fig. 1,

Fig. 3, is an enlarged section, taken on line 3—3 of Fig. 2,

Fig. 4, is a sectional view, taken on line 4—4 of Fig. 3,

Fig. 5, is a top view of the locking mechanism, and

Fig. 6, is a side elevation of the parts shown in Fig. 5, parts broken away.

In the drawings the bowl body is marked 1, the lid thereof 2, covering the seat 3, the small water tank is 4. In the body part 1,

I provide an auxiliary bowl or receptacle 5, which is supported on a shaft 6, mounted in the bearings 7, of the body part 1.

On shaft 6, I securely mount a sector gear 8, which engages the companion gear 9,

mounted on a shaft 10 having the bearings 12 in the body part 1. On the shaft 6, I also mount counter-balance weights 13, to help balance the receptacle 5.

At the upper part of the body part 1 is the opening 14, which carries the lip or ex-

tension 15 to assist in carrying off the gases and fumes, through the vent opening 16.

On the inside of the body part 1, I provide a projection 17 which enters into the receptacle 5, to allow the seal to be formed by the water 18, in said receptacle. This seal is provided against sewer gases.

The receptacle 5 is operated by the shaft 10 being revolved by pushing down on the hand lever 18, which hand lever has an extension 19, which is pivotally mounted to a link 20. At point 21, I pivotally mount one end of a lever 22 which fulcrums on shaft 23 and the other end of said lever is slotted to engage a pin 24, which is mounted on a link 25. A valve arm 26 is pivotally mounted to one end of said link 25 and a valve arm 27 is pivotally mounted to the opposite end of the link 25.

The valve arms 26 and 27 operate the valves 28 and 29 respectively.

On the link 20 I pivotally mount one end of a bell-crank 30, which is fulcrumed at the point 31, on bracket 32; the other end of said bell-crank being pivotally mounted in 80 the lower extremity of a link 33, the upper end of the link being pivotally mounted to one end of a rock lever 34, which is journaled in a bracket 35, supported by the tank 4; at the opposite end of the rocker arm 34, I slidably mount a pin 36 having a contact head 37 and a spring 38, mounted between the head 37 and the bearing 39 of the pin 36. At the point 40 I pivotally mount a trigger arm 41 having the contact head 42 at its 85 one end and at its opposite end having a hook end 43 which engages and disengages with a cam 44, said cam being stationary with the bracket 35. A tension spring 45 has one end fastened in the rocker arm 34 and its other end is fastened on a pin 46, in the tank 4.

I will now describe the water line. An inlet 47 leads to the valve 29 thence to the receptacle 5 through the pipe line 48. I also provide another inlet 49 which leads to the by-pass valve 28, then passes into the tank 4 through the pipe 50.

As the water enters tank 4 it causes the float 51 to rise; said float carrying at its center a rod 52 which is guided in a bracket 53, supported in the tank 4; as the rod 52 comes in contact with the head 37, the lever 41 becomes disengaged from the cam 44, and the spring 45 pulling downward, causes the 105

links 33, 20, 19 and 18 to return to their former position as shown in Fig. 1, and the arms 26 and 27 operating on valves 28 and 29, causing them to close.

5 The water in the tank 4 now drains out through the by-pass valve 28 into pipe line 54 and then into the receptacle 5 and fills the same as shown in Fig. 3.

As the hand lever 18 is pulled down the 10 valves 28 and 29 are both open, the one valve 28 filling the tank 4 as just described and the other valve 29, allows a full pressure of water to flow out into the receptacle 5 to flush same at which time the contents are 15 dumped and pass out through the opening 55 to the sewer.

Both valves being open at the same time as stated, the valve 29 flushes only the length of time it requires to fill the tank 4 through 20 by-pass valve 28, which time is of short duration, and when filled, the float rod 52 operates the trigger action formed by the levers 34, 41 and cam 44, which action cuts off the flow of water and returns all levers back to normal position, as shown in Fig. 1.

This trigger action just described, is the means of positively locking the entire mechanism against operation, except through the 30 hand lever 18.

It will be seen that the ventilating pipe 16 is at the top of the bowl part 1 and extends backwardly as shown, this pipe takes off all the gases and the like before the small bowl 35 5 has been dumped, thus affording ventilation at all times. This pipe leads to the outside.

It will readily be observed that this closet is quick operating, direct flushing and thoroughly sealed, that it is dependable in operation, that it will not readily get out of order and will not freeze in winter, unless under 40 extraordinary circumstances.

I do not wish to limit myself to the specific construction herein shown but claim any modified form which will fall within this specification and claims.

I claim:

1. In a closet of the character described, 50 a closet bowl, an auxiliary pan in the bowl, a relatively small tank associated with the bowl, a pipe leading from the tank to the bowl and having a supply branch, a valve associated with said pipe and adapted in one position to cut off the flow of water from the branch into the pipe and to permit the flow of water from the tank to the bowl, and in another position to permit the flow of water from the branch to the tank, 55 manu-motive means for moving said valve from closed position into the position in which it permits water to flow from the branch into the tank, latching means for holding the manu-motive means in the position to which it has been moved by the 60

operator, a float in the tank arranged to release said latching means, and a device associated with one of said means for returning the manu-motive means to normal position, and the valve to closed position 70 when the latching means has been released.

2. In combination, a closet bowl, a water supply pipe for use in flushing the bowl, a valve controlling the flow of water through said pipe, a small tank, a second pipe connecting the tank and bowl and having a supply branch, a second valve associated with the second pipe and adapted in one position to close the flow from the branch into the second pipe, while permitting flow from the tank to the bowl, and in another position to close the flow through the second pipe to the bowl, while permitting flow from the branch through the second pipe to the tank, said valves normally cutting off the supply of water to the tank or bowl, manu-motive means for simultaneously actuating said valves for placing them in positions in which water flows through the first mentioned pipe to 80 flush the bowl, and water flows through the branch to the second pipe to simultaneously fill the tank, latching means for temporarily holding the valves in the last mentioned positions, a float in the tank arranged to 85 engage the latching means for releasing the latter, and means cooperating with the manu-motive means for returning the valves to their normal positions.

3. A combination as claimed in claim 2, 90 in which the latching means includes a rocking lever, a latching lever pivotally connected to the rocking lever, a spring pressed pin slidably mounted in the rocking lever and engaging the latching lever, 95 and a stationary cam adapted to be engaged by the latching lever when the rocking lever is moved in one direction.

4. In combination, a closed bowl, a dump pan pivotally mounted in said bowl, manu-motive means for dumping said pan, a water supply pipe leading into said bowl, a normally closed valve for controlling the passage of water through said pipe, a small tank, a second pipe placing the tank in communication with the bowl and having a supply branch, a second valve associated with the second pipe and normally cutting off flow from said branch into the second pipe while permitting flow from the tank into the bowl, means for actuating said valves from said manu-motive means, latching mechanism for the manu-motive means, and a float in the small tank arranged to release said latching means.

5. In a closet of the character described, a bowl, a pivoted dump pan arranged in the bowl, manu-motive means for dumping said pan, a water supply pipe for passing water directly from a city main into the 120 125 130

bowl, a normally closed valve arranged in said pipe, a tank, a second pipe placing the tank in communication with the bowl and having a supply branch, a second valve 5 associated with the second pipe, normally closing the flow through the branch while permitting flow through the second pipe from the tank to the bowl, connecting means from the tank to the bowl, connecting means joining the valves to said manu-motive 10 means, whereby when the manu-motive means is operated, the valves will be manipulated to permit the flow of water through the first mentioned pipe into the bowl, and through the branch into the tank, latching means operatively connected to the 15 connecting means for holding the manu-motive means in the position to which it has been moved by the operator, a float in the tank for releasing said latching means, and a device for returning the parts 20 to normal condition after the latching means has been released.

In testimony whereof, I affix my signature at Cincinnati, Ohio, this 29th day of May, 1926.

ARTHUR PATTERSON.
